A. M. RIFFLE

GARMENT HANGER

Filed March 9, 1922

Attorney

UNITED STATES PATENT OFFICE.

ALVA M. RIFFLE, OF QUEENS, WEST VIRGINIA.

GARMENT HANGER.

Application filed March 9, 1922. Serial No. 542,390.

To all whom it may concern:

Be it known that ALVA M. RIFFLE, a citizen of the United States of America, residing at Queens, in the county of Upshur and ⁵ State of West Virginia, has invented new and useful Improvements in Garment Hangers, of which the following is a specification.

The object of the invention is to provide a simple and efficient garment hanger and ¹⁰ stretcher particularly adapted for coats and trousers whereby the shape of the same may be preserved and the crease in trousers restored, the device being of such a construction as to permit of folding into compact ¹⁵ form for storage in a trunk, grip, or valise; and with these objects in view the invention consists in a construction and combination of parts of which a preferred embodiment is shown in the accompanying drawings, ²⁰ wherein:

Figure 1 is an elevation of a hanger embodying the invention.

Figure 2 is an edge view of the same.

Figure 3 is a perspective view of the coat ²⁵ hanger.

The device consists essentially of a stem ¹⁰ having a cross bar ¹¹ to the extremities of which are pivotally connected side bars ¹² which in common with the cross bar carry ³⁰ clasps ¹³ for engagement with the garment, such as a pair of trousers located between the bars in position to be stretched transversely by outward movement of the side bars incident to the tension of a spring ¹⁴ ³⁵ connecting the upper ends of the side bars above the cross bar ¹¹. The stem ¹⁰ is provided with a supporting hook ¹⁵ and at an intermediate point is bowed laterally to form

a loop ¹⁶, and with this loop are engaged the inner ends of shoulder arms ¹⁷ each of which ⁴⁰ is of looped construction with the extremities provided with hook members ¹⁸ for interlocking engagement with the upper and lower sides of the loop ¹⁶, so that said arms may be supported in the transversely extending ⁴⁵ position indicated in Figure 1. To secure the extremities of the loop sides forming the shoulder arms in engagement with the loop of the stem there is employed a movable ring ¹⁹ adapted to occupy a position in oblique intersection with the loop ¹⁶ to lock the inner ends of the shoulder arms in their proper relations thereto. Obviously ⁵⁰ in order to fold the support the ring may be disengaged from the loop ¹⁶ and permitted to drop whereupon the hooked extremities of the shoulder arms may be disengaged from the loop ¹⁶.

Having described the invention, what is ⁵⁵ claimed as new and useful is:—

A garment hanger comprising a stem formed from wire and provided at a point between its ends with a loop extending beyond one side of the stem and merging into a hump disposed at the opposite side of ⁶⁰ the stem, shoulder arms having hooked ends adapted to engage in said loop, and a ring mounted upon the stem and adapted to engage over the end portions of the loop and the hump and receive the inner end portions ⁶⁵ of the arms, whereby the arms are loosely connected with the stem.

In testimony whereof he affixes his signature.

ALVA M. RIFFLE.
